Primary Examiner — Karen S Acker

(74) Attorney, Agent, or Firm — Knobbe, Martens, Olson & Bear, LLP

(57) **CLAIM**

The ornamental design for a seating, as shown and described.

DESCRIPTION

FIG. 1 is a top, front, and right side perspective view of a seating;

FIG. 2 is a bottom, rear, and left side perspective view thereof;

FIG. 3 is a front view thereof;

FIG. 4 is a rear view thereof;

FIG. 5 is a left-side view thereof;

FIG. 6 is a right-side thereof;

FIG. 7 is a top plan view thereof; and,

FIG. 8 is a bottom plan view thereof.

The broken lines and the areas adjacent to the side of the article drawn in solid line depict portions of the seating that form no part of the claimed design.

1 Claim, 8 Drawing Sheets
